WHEEL COT

Tore Ericsson, Stockholm, Sweden, assignor to
 Aktiebolaget Sangfabriken, Stockholm, Sweden,
 a corporation of Sweden

Application September 7, 1943, Serial No. 501,489
 In Sweden January 13, 1943

4 Claims. (Cl. 280—33.44)

The present invention refers to an improvement in cots and is particularly intended to be used at maternity hospitals. Various sorts of cots are known, to wit, such cots as are supported by legs provided with supporting casters, cots with legs but without supporting casters, and cots without a supporting frame that are intended to be supported by brackets on a wall. As a baby must be removed several times a day—for nursing etc.—from the babies' ward and to the confined mother in another ward, or room, it has since long been desired to solve this removal problem in a satisfactory way. When beds on legs but without supporting wheels are used, the baby is lifted over into another cot, which together with generally three other cots can be placed on a carriage from which the cot in question, after being conveyed to the mother's room, may be lifted over to the mother's bed at the foot of which it is generally placed. Such a removal is especially inconvenient and involves a waste of time on account of the fact that the baby must be removed from its own bed to another cot, as well as the fact that the bulky carriages necessitate rather much space, no matter whether they be in the mothers' ward or in the babies' ward. The removal of the baby from its own bed to another cot can be eliminated, if the baby's bed consists of a detachable cot supported by a bracket, whereby the cot can be lifted over onto the carriage without further ado. This solution, however, has not enabled the elimination of the bulky carriage conveying the cots. Since cots supported by legs have been provided with supporting casters, the carriage has admittedly become unnecessary and this has made it possible for the baby to remain in its own bed during removal of the latter, but the actual question of removal is still very troublesome, as a nurse cannot remove more than one or, at most, two cots at a time, which necessarily involves a considerable waste of time.

The present invention solves this problem completely by providing means whereby the baby may remain in its own caster supported cot, no extra carriage being necessary, and a greater number of cots, say six, being movable at a time by a single nurse. This is achieved by means of the invention by the provision of connecting means provided on the relatively opposite sides of the cots, said connecting means being such that either two or more cots may be detachably connected in a row for the removal of the hitched cots as a whole on their casters.

In order to readily understand the invention

and easily to put it into effect, it will now be described by reference to the accompanying drawing which illustrates an embodiment of the same. In the drawing,

Fig. 1 is a perspective view of three cots hitched to one another in accordance with the invention.

Fig. 2 is drawn on a larger scale and illustrates perspectively the remotest of the three cots shown and seen in the direction of the arrow P in Fig. 1.

Fig. 3 shows on a still larger scale a fragment of the connecting device.

Finally, Fig. 4 is a fragmentary view like Fig. 3 but showing a modified embodiment of the invention.

In the illustrated embodiment shown by way of example in Figs. 1-3, the connecting means comprises a wire strap 2 disposed along one side of each cot 1, the shanks 3 of the straps being welded to the legs 5 extending from the corners 10 of the cot frame and provided with casters. That part of the strap 6 connecting the shanks 3 extends in spaced relationship to, and along, the said side of the cot 1 parallel to the top edge of the cot. On the opposite side of the cot, a wire strap 7 is adapted in a similar way, the shanks 8 of said strap 7 being bent down and together with the part 9 connecting said shanks adapted to be introduced into the first mentioned part 6 of a straight strap 2 adapted on the opposite side of another cot. The shanks 8 of the "bent" strap 7 converge somewhat in a downward direction, and in a gentle curve they merge into the horizontal part 9 of the strap. By this means it is easier to introduce the shanks 8 of the "bent" strap 7 between the shanks 3 of the strap 2 when connecting two cots, and at the same time to obtain an effective lateral guiding control. Fig. 3 shows clearly, how the strap 2 engages the strap 7, this hitching being effected simply by lifting up the 15 right hand side of the left hand cot and hitching it onto the right cot. Thanks to the efficient lateral guiding, a single nurse, preferably by pushing the last of the three cots (or a plurality) shown in Fig. 1, can easily move and maneuver the whole row. The disconnecting of the various cots on their arrival is performed in the converse way by placing aslant and subsequently unhitching one cot after the other. Even cots having but 20 one pair of casters (see Fig. 1, the middle cot) 25 may be removed in this way, as those legs without casters are held up from the floor by means of the connecting means.

The connecting means, however, may be constructed in various ways within the scope of the invention. Thus, the shanks 8' of the bent strap

1' may be bent downward instead of upward, whereby the same good result is obtainable. It would be going too far to mention all modifications of the connecting means useful and suitable in this connection, and the examples illustrated above are therefore to be considered sufficient for illustrating the invention. Connecting means also without the aforementioned lateral guiding means may be used in which case the nurse must draw, instead of push, the row of cots.

What I claim and desire to secure by Letters Patent is:

1. A device for detachably connecting a plurality of wheel-cots at relatively opposite ends enabling a row of cots thus formed to be moved as a single unit, which comprises two horizontally extending straps, one on either side of a cot, said straps being in spaced relationship to said respective sides and fixed to the cot by means of shanked ends in the vicinity of the corners of the cot, the shanked ends of one strap being arcuated downward, the part of the strap connecting said arcuated shanks being adapted to come into engagement between the shanks of, and on the inner side of, a strap of another cot for hitching same thereto.

2. A device for detachably connecting a plurality of wheel-cots at relatively opposite ends enabling a row of cots thus formed to be moved as a single unit, which comprises two horizontally extending straps, one on either side of a cot, said straps being in spaced relationship to said respective sides and fixed to the cot by means of shanked ends in the vicinity of the corners of the cot, the shanked ends of one strap being arcuated upward, the part of the strap connecting said arcuated shanks being adapted to come into

5 engagement between the shanks of, and on the inner side of, a strap of another cot for hitching same thereto.

3. A device for detachably connecting a plurality of wheel-cots at relatively opposite ends enabling a row of cots thus formed to be moved as a single unit, which comprises two horizontally extending straps, one on either side of a cot, said straps being in spaced relationship to said respective sides and fixed to the cot by means of shanked ends in the vicinity of the corners of the cot, the shanked ends of one strap being arcuated, the part of the strap connecting said arcuated shanks being adapted to come into engagement between the shanks of, and on the inner side of, a strap of another cot for hitching same thereto.

4. A device for detachably connecting a plurality of wheel-cots at relatively opposite ends enabling a row of cots thus formed to be moved as a single unit, which comprises two horizontally extending straps, one on either side of a cot, said straps being in spaced relationship to said respective sides and fixed to the cot by means of shanked ends in the vicinity of the corners of the cot, the shanked ends of one strap being arcuated, the part of the strap connecting said arcuated shanks being adapted to come into engagement between the shanks of, and on the inner side of, a strap of another cot for hitching same thereto, wherein the said arcuated shanks converging with respect to each other and curvilinearly merging into the part joining the shanks, thereby enabling an easy introduction of the last said part of the strap between the shanks of a corresponding strap of a juxtaposed cot.

TORE ERICSSON.
